CLAIM

The ornamental design for a bank with multiple compartments, as shown and described.

DESCRIPTION

FIG. 1 is a perspective view of a bank with multiple compartments, showing our new design with the lid shown in a closed position;

FIG. 2 is a front view of FIG. 1;

FIG. 3 is a back view of FIG. 1;

FIG. 4 is a left side view of FIG. 1;

FIG. 5 is a right side view of FIG. 1;

FIG. 6 is a top view of FIG. 1.

FIG. 7 is a bottom view of FIG. 1.

FIG. 8 is a perspective view of FIG. 1 shown with the lid in an open position;

FIG. 9 is a front view of FIG. 8;

FIG. 10 is a back view of FIG. 8;

FIG. 11 is a left side view of FIG. 8;

FIG. 12 is a right side view of FIG. 8;

FIG. 13 is a top view of FIG. 8; and,

FIG. 14 is a bottom view of FIG. 8.

The broken lines shown in the drawings represent portions of the bank with multiple compartments that form no part of the claimed design.
